UNITED STATES PATENT OFFICE.

MARTIN L. PATTERSON, OF BOGOTA, NEW JERSEY, ASSIGNOR TO THE SPERRY GYRO-SCOPE COMPANY, OF BROOKLYN, NEW YORK, A CORPORATION OF NEW YORK.

SAFETY STOP FOR SEARCHLIGHTS.

Application filed April 24, 1922. Serial No. 556,348.

This invention relates to searchlights adapted to be controlled from some distant point to vary its position in azimuth and in elevation or depression. Such control is usually accomplished by motors, the circuit through which may extend to any desired distance. The elevation and depression of a searchlight is usually between definite predetermined limits, relatively fixed stops being provided against which the searchlight strikes to limit its movement. The force of the blow caused by the lamp, rotating with the full speed transmitted to it by the elevating motor, striking against the stops was sufficient to cause strains on the gears, shafting, pins and other parts of the searchlight, and to cause possible damage to the motor due to the excess current. It is an object of this invention, therefore, to provide means for braking the movement of the lamp as it approaches the stops in elevating or depressing. This is accomplished without opening the motor circuit, otherwise it would be impossible to reverse the movement of the lamp to move it away from the stops. The present invention therefore provides in the closed circuit of the elevating motor means for reducing the speed of the motor as the lamp approaches the stops which limit the elevation or depression. For this purpose there is provided in the circuit of the elevating motor a limit switch so designed that, when opened, the motor circuit includes a fixed resistance which cuts down the speed and power of the motor. When said switch is closed, the resistance is short-circuited so that the elevating motor is connected directly to the line. Means are provided whereby said switch may be opened at any predetermined maximum elevation or depression.

It is not unusual to provide stops for limiting the movement of the searchlight in azimuth, the light being free to make complete rotations in either direction. Where, however, limiting stops are provided to limit the movement in azimuth, it will be understood that the same invention hereinafter described in connection with the elevating motor can be applied in connection with the azimuth motor.

Other objects and advantages will herein-after appear.

The accompanying drawing illustrates

mainly in diagrammatic form, an embodiment of my invention.

The invention is applied to a searchlight having an azimuth motor A and an elevating motor E, as disclosed in the application of Theodore Hall, Serial No. 319,383, filed August 23rd, 1919, Pat. No. 1,537,770, May 12, 1925. Each of said motors has a field 10 and 11, respectively, energized from the main current leads 12 and 13 by lead-lines 14, 15 and 16, 17 respectively. The armature 18 of the azimuth motor is connected by leads 20 and 21 to an azimuth controller AC, while armature 19 of the elevating motor is connected by leads 22 and 23 to an elevating controller EC. The azimuth motor 75 is generally mounted on a fixed base since it rotates the entire lamp, and the leads may therefore be connected directly thereto, but the elevating motor moves with the main frame of the searchlight and it is therefore necessary to provide slip-rings 30 and 31 for conducting the current thereto.

For controlling the speed of either motor, both of said controllers are wired to a potentiometer P. Each controller comprises two sets of contacts here shown as 1 to 8 inclusive and contacts C similarly arranged on opposite sides of an arc, like contacts being joined together. A double contact member comprising two arms 35 and 36 in fixed relation to each other cooperates with said contacts, each arm cooperating with a set of contacts on one side of the arc. It will be apparent that as the contact member is rotated in one direction or the other, one arm will move upwardly on one set of contacts and downwardly on the other set. In its central position both arms of the contact member engage contacts C, and hence the circuit of the armature lies through lead 20 across contacts C to lead 21, thus excluding the potentiometer entirely from its circuit. Since there is no drop in potential in the armature circuit in this position of the contact arms, the motor is at rest. When, however, the contact member is rotated through one contact space, for example, contact arm 35 engages contact 4 and contact arm 36 engages contact 5, the circuit is then through lead 20 to contact 5, lead 45 to contact 5 of potentiometer P, through the potentiometer to contact 4, lead 44 to contact 4 of the controller, and lead 21

to the armature. There is thus included the drop in potential included between contacts 4 and 5 of the potentiometer, said drop being a fraction of the total drop between contacts 1 and 8 of the potentiometer which corresponds to the position of the contact member where one arm engages contact 1 of the controller and other other arm engages contact 8 of the controller. By rotating the contact arm, it is thus apparent that any desired drop in potential may be introduced in the armature circuit. It will also be apparent that the direction of rotation of the motor may be controlled by moving the contact member clockwise or counterclockwise from the CC position, so that the potential drop is in one direction or the other.

The controllers AC and EC for the azimuth and elevating motors, respectively, are similar, and by connecting the contacts of both controllers to the same junctions 41' to 48' inclusive, the same leads 41 to 48 inclusive and the same potentiometer P may be utilized in connection with both controllers. It will be obvious that both controllers may be operated simultaneously.

Scales are usually provided to enable the operator to read the number of degrees of turn in azimuth and in elevation, and lights 30 50, here shown as connected to the main line, may be provided adjacent said scales to facilitate reading thereof.

The controllers AC and EC, junction-box J, in which are located the junctions 41' to 48' inclusive and the junctions of leads 20, 21, 22 and 23, are preferably located at a distance from the lamp and its control motors, and a coupling K is preferably interposed to enable the plurality of connecting leads to be readily connected to or disconnected from the lamp.

As hereinbefore pointed out, there are usually provided stops on the supporting frame and shown diagrammatically at S 45 which limit the elevation and depression of the lamp by engaging lugs, indicated diagrammatically at L', on the drum, and it is apparent that motor E, rotating the lamp, will cause the latter to strike the stops while 50 it is traveling at full speed, since the operator stationed at a distance does not know when the lamp is approaching the stops. It is not desirable to interpose a circuit-breaker to be operated by the lamp before 55 reaching the stops, since it would then be impossible to operate the lamp in the reverse direction, without actuation of hand-switches since the circuit is open. This invention therefore introduces a braking element at the proper time, without opening 60 the circuit through the motor. The circuit through the armature of motor E from slip-rings 31 ordinarily extends through lead 52 (which is a continuation of conduit 65 22), limit switch L, conduit 51, and conduit

53 (which is a continuation of conduit 23). When the lamp approaches its limiting stops, means are provided for breaking the circuit through switch L, and the circuit then extends from slip-rings 31 through resistance R (connected in series in the circuit) and lead 53. The introduction of this resistance in the circuit slows down the motor to such an extent as to prevent damage which might otherwise be caused by 75 the striking of the lamp against the stops. Ordinarily therefore the circuit is shunted across resistance R so that substantially all of the current flows through the shunt.

For operating the limit switch when the lamp approaches a limiting stop, the frame 55 of the lamp which swings about a horizontal axis during elevation or depression of the light, is provided with a cam 60 so positioned shortly before the lamp engages the stops, as to contact with a movable bar 61, which carries leaf spring contacts 62 normally in engagement with contacts 63, to depress said bar against the action of a spring 64 and break the circuit through leads 52 and 51 to the armature 19. The circuit through said armature now includes resistance R, and this circuit will be maintained as long as cam 60 engages bar 61. At any time, however, the lamp may be moved in the opposite direction by merely rotating the contact arms 35, 36 in the desired direction. Just before the lamp reaches its opposite limit stop, a second cam 68 may be provided to engage and depress bar 61. By providing a pin and slot connection 69, 70 between each cam and the frame 55 of the lamp, the point at which the motor is slowed down can be varied at will in accordance with the particular conditions.

In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having herein described my invention what I claim and desire to secure by Letters Patent is,

1. In combination with a movable device, electric means for moving said device, said means including a controller and an electric motor, a circuit for transmitting a relatively large current to said motor and a second circuit for transmitting a relatively small cur-

rent to said motor, means for limiting the movement of said device, means normally rendering one of said circuits effective, means for rendering ineffective the normally effective circuit and rendering the other of said circuits effective, as the device approaches said limiting means, to vary the speed of the device, and means permitting said first means to reverse the direction of movement of said device in any position thereof without breaking the circuit between said controller and said motor.

2. In combination with a movable device, electric means for moving said device, said means including a controller and an electric motor, a circuit for transmitting a relatively

large current to said motor and a second circuit for transmitting a relatively small current to said motor, means for limiting the movement of said device, means normally rendering said first circuit effective, means for rendering said first circuit ineffective and said second circuit effective, as the device approaches said limiting means, for reducing the speed of the device, and means permitting said first means to reverse the direction of movement of said device in any position thereof without breaking the circuit between said controller and said motor.

In testimony whereof I have affixed my ³⁰ signature.

MARTIN L. PATTERSON.
